DIESEL ENGINE COMPANY, OF ST. LOUIS, MISSOURI, A CORPORATION OF MIS-
SOURI.

REVERSING-GEAR FOR INTERNAL-COMBUSTION ENGINES.

1,163,160.

Specification of Letters Patent.

Patented Dec. 7, 1915.

Application filed August 28, 1913, Serial No. 787,066. Renewed May 5, 1915. Serial No. 26,138.

To all whom it may concern:

Be it known that I, RODOLPHE LANDOLT, a citizen of the Republic of Switzerland, residing at Zurich, Switzerland, have invented certain new and useful Improvements in Reversing-Gear for Internal-Combustion Engines, of which the following is a full, true, and complete specification.

The invention concerns a reversing arrangement for internal combustion engines and especially for the multiple cylinder type for purposes of locomotion, whereby a special mechanism is provided by means of which the engines may work in the ahead or astern direction, while a second mechanism controls the valve gear for starting, working and stop. This type of engine is usually started by means of compressed air and afterward by a continuous movement gradually switched on to oil for normal working. In this way it can easily happen that in consequence of the inattention or a mistake on the part of the engine driver, the operations for reversing may be carried out falsely; that is to say before the air or the fuel has been shut off. This arrangement has considerable disadvantages.

The present invention overcomes these disadvantages in providing a special control by means of which the mechanism for ahead or astern working and the mechanism for starting, running and stop are so interconnected that the former can only be operated when the latter is in the stop position.

In the drawings, Figure 1 is a front elevation of a reversing engine control device; Fig. 2 is a section thereof; Fig. 3 a detail of the bolt; and Fig. 4 an indication of the combination of the device with the engine parts controlled by it.

A is the handwheel by means of which the valve gear is operated for the starting with air running and stop positions (valve gear I).

B is the reversing lever by means of which the engines are set to run ahead or astern (valve gear II).

On the spindle of the hand-wheel A a pinion C is mounted which drives the spur wheel D. The forward part of the wheel D is turned cylindrical and provided with the slots v in which the rollers r operate. The rollers r are mounted on the end of the bolts b, the movement of which is guided

in the main casting K. The length of these bolts is such, that when the rollers r do not rest in the slots v, their other ends project beyond the outside surface of K, that is to say, when the gear for operating the air or fuel (valve gear I) is not in the stop position. In Fig. 1 the stop position is further indicated by means of the pointer s fixed on the wheel D which comes exactly opposite the pointer p fixed on the casting K.

When the bolts b do not project, the reversing lever B may be moved from the ahead position V in the direction of the arrow into the astern position R. Should the hand-wheel A be revolved either right or left, that is to say to admit the air or fuel, the wheel D will likewise be revolved, and the rollers r will be operated by the smooth circular surface D' of D, so that the points of the bolts b will protrude and prevent the reversing lever B being again revolved into the opposite position. In this way the lever for the ahead and astern directions is controlled so long as the mechanism operating the air and fuel is not in the neutral or stop position. The engine driver can therefore on reversing make no mistake. These two mechanisms are further capable of being operated by means of auxiliary engines.

The valve gears I and II are merely indicated in the drawings because methods and means for setting valve-operating elements for forward or reverse running, and also for air or combustion operation and stopping, are well-known and form no part of the novelty of the invention. Briefly, the shaft 1, to which the lever B is secured, operates one or more connections 2 and 3, of which the connection 3 may shift the eccentric fulcrum of the fuel valves in the known manner to cause them to open at the proper times for running in one direction or the other, while the connection 2 may effect the shifting of any other element which it may be desirable to adjust in connection with the reversing operation. The hollow shaft 5, to which the wheel D is united and which surrounds the shaft 1, is shown provided with a pair of disk-form function cam-grooves 9 and 10, one adapted to govern one group of the engine cylinders through connections 9^a and the other to govern another group through connections 10^a. As to these elements, therefore, the drawings are merely

- 2
- indicative of suitable connections whereby turning of the hand wheel A from a position in which both the air starting and the fuel valves are out of action brings first the 5 starting valves into operation, and then, in proper sequence, renders these valves inoperative and causes the corresponding fuel valves to perform their functions. Restoration of the hand wheel to the original position safely cuts off both starting air and 10 fuel, and it is this position of part A which permits operation of the hand lever B, as already set forth.
- What is claimed as new is:
- 15 1. In a reversible internal combustion engine, two independently operable mechanisms, one controlling the reversing and the other controlling air starting, combustion running and stopping of the engine, and 20 means whereby the former mechanism can be operated only when the latter is in the stop position.
2. A control device for combustion engines comprising a device for controlling the 25 air starting and fuel valves, a second independently operable device serving to set the engine for reverse running, a blocking means for the latter device, and means whereby the first device sets the blocking 30 means in operative position while the starting or fuel valves are in operation.
3. A control device of the kind described comprising a reversing shaft, a starting and combustion-controlling shaft, a gear 35 through which the same is rotated, means for blocking the reversing shaft, and means on such gear for operating the said means.
4. A control device of the kind described, comprising a reversing shaft and locking 40 means therefor; a starting and combustion controlling shaft, said shafts being independently operable, a part on said starting and combustion controlling shaft bearing a reference index therefor, and means on such 45 part for controlling the said locking means.
5. A control device of the kind described, comprising a starting and combustion controlling shaft, a gear thereon and an actuating pinion for such gear through which it 50 may be manually rotated, in combination with a reversing shaft, means for blocking the movement thereof, and means revolving with said gear to operate said blocking means.
6. A control device of the kind described, 55 comprising two control shafts, the one being tubular and inclosing the other, in combination with means controlled by the position of one shaft to prevent operation of the other.
7. A control device of the kind described comprising two control shafts, one of which surrounds the other, a rotating member on the outer shaft through which it is operated, and means on said member for preventing 60 operation of the other shaft.
8. A control device of the kind described comprising a casing bearing a reference index, a pinion therein, a gear driven by the pinion and bearing a reference index exposed to view from the exterior of the casing, a control shaft operated by the said gear, a second control shaft, and means for locking the same controlled by the position 65 of the said gear.
- 75 9. A control device of the kind described, comprising a control shaft, a tubular control shaft surrounding it, a manual operating handle in the inner shaft, a concentric gear on the tubular shaft, and a manually operated pinion for rotating the gear, in combination with means operated with one of said shafts for preventing operation of the other.
10. In a reversible internal combustion engine, the combination of a reversing device, 80 a second mechanism controlling air starting, combustion running and stopping of the engine, and stops operative in a plane perpendicular to the axis of the reversing 85 device and controlled by said second mechanism so as to block the path of the reversing device when the second mechanism is in starting or working position.
- In testimony whereof, I have signed this 90 specification in the presence of two witnesses.
- 95 RODOLPHE LANDOLT.
